(57) **CLAIM**

I claim the ornamental design for callus remover, as shown and described.

DESCRIPTION

FIG. 1 is a bottom view of one embodiment of the new design;

FIG. 2 is a top view thereof;

FIG. 3 is a right side view thereof;

FIG. 4 is a left side view thereof;

FIG. 5 is a front end view thereof;

FIG. 6 is a back end view thereof taken from the handle portion break point;

FIG. 7 is a bottom view of a second embodiment of the design wherein the modification resides in the omission of the stone;

FIG. 8 is a left side view thereof;

FIG. 9 is a front end view thereof; and,

FIG. 10 is a back end view thereof taken from the handle portion break point.

The broken line in FIG. 1 depicting a rope and in FIGS. 1-4 and 7-8 depicting a handle portion is for illustrative purposes only and forms no part of the claimed design.

The broken lines in FIG. 7-10 depicting a stone are for illustrative purposes only and form no part of the design for the second embodiment.
